FRANCIS E. PATTERSON, OF WILMINGTON, DELAWARE.

EXERCISING-MACHINE.

1,137,349.

Specification of Letters Patent. Patented Apr. 27, 1915.

Application filed January 27, 1914. Serial No. 814,609.

To all whom it may concern:

Be it known that I, FRANCIS E. PATTERSON, a citizen of the United States, and a resident of Wilmington, in the county of 5 New Castle and State of Delaware, have invented certain new and useful Improvements in Exercising-Machines, of which the following is a specification.

My invention relates to improvements in 10 exercising machines and more particularly to improvements in means for exercising and developing those muscles of the left arm, left side, and back (or the right arm, right side, and back if the player be a left-handed one) which are used by golf players 15 in playing the game. In this specification it will be assumed that the player is right-handed, if he is a left-handed player it will be understood that the terms right or left 20 herein employed, should be reversed.

For making a successful golf stroke the player should grasp the grip of the club at its upper end with the left hand, the little finger of the right hand, which is placed below the left, overlapping the forefinger of the left and in making the backward swing, both hands are raised, the left in control, approximately, to the level of the right shoulder. The stroke delivered from this 30 position is a sweeping one and at its finish both hands are raised above the left shoulder.

In lifting the club to begin the backward swing the two extensors carpi radialis, long 35 and short, passing from lower part of upper arm to elbow and wrist, on thumb side, are brought into play and when the club is fully raised the left hand is, as before stated, approximately at the level of the right shoulder. The club is now swept downward and the triceps extensor, the muscles of the 40 shoulder group, of the shoulder girdle group and the lower back muscles are brought into play, and at the instant contact of the club 45 head with the ball, a snappy or whipping torsional motion is given to the stroke by the use of the extensor carpi ulnaris, passing from elbow to wrist on little finger side. The stroke is then practically completed but 50 there is an after swing due to the momentum acquired and during such swing restraining muscles are brought into play.

The object of this invention is to provide 55 an exercising device adaptable to the various peculiar movements of a golf stroke and use-

ful in developing and strengthening the particular muscles used in the game of golf.

The purpose of my invention is to exercise and develop the above muscles, and further, by means of a grip that can only be 60 grasped conveniently in one position, my invention is intended to instruct the operator in the proper method of grasping the club to obtain the best results in practice, and to bring the aforesaid muscles into play.

In the accompanying drawings forming part of this specification, and in which similar letters of reference indicate similar parts throughout the several views: Figure 1, is a 65 diagrammatic view of my apparatus arranged to exercise and develop the muscles used in lifting the club preparatory to making the swinging stroke: Fig. 2, a similar 70 view showing the arrangement of the apparatus for exercising and developing the muscles used in making the first or downward part of the swinging stroke: Fig. 3, a similar 75 view showing the arrangement of the apparatus for exercising the muscles brought into play at the moment the ball is struck by the 80 club: Fig. 4, a front elevation of a spring actuated drum for taking up the slack of the cord: Fig. 5, a section of the drum on line C—D Fig. 5, and Fig. 6 a section on 85 line A—B of Fig. 4: Fig. 7, a top view of molded grip adapted to be grasped by the hand of the exerciser, and Fig. 8, a view of 90 this grip as grasped by the left hand.

This golfer's exercising device comprises 95 in its essential features a flexible member under tension and having one end free and a golf club grip connected in alinement with the free end of said flexible member. The flexible member is extensible by any suitable means, the means shown for this purpose being a mechanical tension device with which one end of said flexible member is connected. The flexible member is preferably a cord.

In the embodiment herein illustrated, 1 is 100 a cord, 2 a pulley around which said cord passes, and 3 a rotatable retractive carrying means for one end of the cord which permits it to be extended when its free end is drawn upon and which gathers it up immediately 105 when tension upon its outer end is relieved. For my purposes this cord carrying means should exert a substantially uniform pull upon the cord at all times, that is to say the pull exerted upon the cord by this retractive device should be substantially the same when 110

the cord is fully wound upon the spool 5 and when partly or fully withdrawn therefrom. To this end the spool 5 is carried loosely upon a shaft 6, which is carried in any convenient manner, and a coil spring 7 is fastened at one end to this shaft and at the other to the inner periphery of the spool 5. This spring is so constructed as to give a substantially uniform retractive pull upon the spool as the latter is revolved and the cord drawn off. This is important in that the object of my invention is to reproduce as nearly as may be the effect of swinging a golf club. In the embodiment shown the construction of the spring to effect the substantially uniform retractile pull thereof is a gradual increase in thickness of said spring from its inner end attached to the shaft 6 to its outer end attached to the barrel 5, as shown in Fig. 5.

The grip 8 has substantially the form of a golf club grip and one end thereof is connected with the free end of the cord 1 and the other end is free from any connection, whereby it may be grasped by the hand and moved in any direction as desired. This cord between the grip and spool, passes around the pulley 2 which is capable of two or more adjustments which permit the operator to describe, with the shaft of the grip, two or more segments of the curve described by the shaft of the golf club in making the actual stroke. The greater the number of adjustments the more nearly do the segments approach the actual curve and in this manner the muscles used in making the actual stroke are successively brought into play. Three adjustments, or positions of pulley 2, are shown in Figs. 1, 2 and 3 respectively.

To become an expert player the upper end of the golf club should be grasped, if the player is a right-handed one, with the left hand, the stroke is delivered with the left arm, and the right hand, which merely guides the club, grasps it just below the left hand as before described. It is most important that the left hand grasp the club properly and in order that my apparatus may instruct in this and at the same time develop the correct muscles, I model the grip so that the operator cannot well grasp it in any but the approved manner. Upon its top the grip has a depression A which fits the thumb, and upon its sides and bottom depressions B for the fingers and for the palm of the hand. These are shown in Fig. 7 and are, in fact, facsimiles of the impression formed in soft material by the hand of an expert golfer. In Fig. 8 the grip is shown grasped properly by the left hand.

The grip 8 being attached to the cord 1 and this cord passing around pulley 2 and being attached to the tension device the apparatus is in readiness to be used. As I have stated before the stroke is a swinging one. This stroke for purposes of description may be divided into three parts, first a downward movement, second a horizontal movement, third an upward movement. In the downward and horizontal movements certain muscles of the arm and back are brought into play, and upon the upward stroke, muscles of the forearm and wrist are used. These have been before enumerated and on account of them the apparatus may be arranged, by shifting the pulley 2, so as to exercise any of them which is done by pulling upon the cord through the grip 8.

Having thus described my invention I claim as new and desire to secure by Letters Patent:

1. A golfer's exercising device comprising a flexible member under tension and having a free end, and a golf grip having one end free and the other end connected with the free end of said flexible member.

2. A golfer's exercising device comprising a flexible member under uniform tension and having a free end, and a golf club grip having one end free and the other end connected with the free end of said flexible member.

3. A golfer's exercising device comprising a tensional holding device, a flexible member connected therewith and having one end free, and a golf club grip connected with the free end of said flexible member in alinement therewith.

4. A golfer's exercising device comprising a tensional holding device adjustable into different positions for the successive segments representing a golf club swing, a flexible member connected therewith and having one end free, and a golf club grip connected with the free end of said flexible member in alinement therewith.

5. A golfer's exercising device comprising a spring retracted rotary spool, a cord woundable on said spool and having one end connected therewith and the other end free, a pulley adapted to be placed in different positions and over which said cord passes, and a grip having substantially the form of a golf club grip, said grip having one end free and the other connected with the free end of said cord.

FRANCIS E. PATTERSON.
